SOAP MOLD.

(Application filed July 31, 1901.)

(No Model.)

2 Sheets—Sheet 2.

UNITED STATES PATENT OFFICE.

WASHINGTON BERRY, OF CHICAGO, ILLINOIS.

SOAP-MOLD.

SPECIFICATION forming part of Letters Patent No. 695,028, dated March 11, 1902.

Application filed July 31, 1901. Serial No. 70,365. (No model.)

To all whom it may concern:

Be it known that I, WASHINGTON BERRY, a citizen of the United States, residing at Chicago, in the county of Cook and State of Illinois, have invented certain new and useful Improvements in Soap-Molds, of which the following is a specification.

This invention relates to improvements in molds for producing cakes of soap containing inserts.

The primary object of my device is to provide a mold in which a mass of soap may be cast around properly spaced and located inserts in such a manner that the mold may be separated from the mass of molded soap and the mass of soap may be cut up into numerous cakes each containing an insert.

My present invention relates especially to a mold which is adapted for convenient and commercial use in the production of laundry and transparent soap and the like.

These and such other objects as may hereinafter appear are attained by the devices illustrated in the accompanying drawings, in which—

Figure 1 represents a cross-section through a soap-mold containing my improvements. Fig. 2 represents a side elevation of the same with part of the side broken away. Figs. 3, 36 4, and 5 show details of construction. Fig. 6 indicates an end elevation, partly broken away, of a modified form of my invention. Fig. 7 shows a side elevation, partly broken away, of the mold shown in Fig. 6. Fig. 8 is 35 a horizontal section on the line 8 8 of Fig. 7. Figs. 9 and 10 are enlarged details of the construction of the modified form shown in Figs. 6, 7, and 8; and Fig. 11 illustrates a modification in the manner of locating the inserts.

Like letters of reference indicate corresponding parts in the several figures of the drawings.

In the art of soap-making it is customary to cast laundry soap in large masses in a 45 knockdown mold carried on trucks. After the soap has solidified the sides of the mold are removed, leaving the solid mass of soap upon the trucks, and this mass is then cut into cakes in any convenient manner, but 50 usually by pushing the truck against a tightly-stretched wire, which cuts cleanly through the mass of soap at any desired point.

In the drawings I have shown my invention embodied in a mold of this general description.

55

Referring by letter to the accompanying drawings, A indicates trucks, upon which is mounted a base-board B, upon the upper surface of which is attached a base-plate C, which is provided with a number of properly-spaced screw-threaded perforations c.

D indicates side boards, to the inner faces of which and adjacent to their lower edges are attached supports d. The simplest form of these supports consists of angle-irons, as 60 shown in the drawings.

E indicates end boards provided with like supports e.

F indicates clamping-bars disposed at each end of the mold and, if desired, also midway 70 between the ends and connected by stay-bolts G, which extend through clamping-bars F, side boards D, and across the mold are formed with a head at one end and are engaged by nuts g at the other end.

75

H indicates end irons, the ends of which are fitted within slots in the side boards D.

In assembling my mold, the side boards D are put in place, resting upon the supports d; the end irons H are fitted within slots provided for them in the side boards D; and, the side boards being held firmly in position, the end boards E are then put in place resting upon their supports e, and inner faces thereof adjacent to their lower edges abutting 85 against corresponding ends of the base-board B, the inner faces of the end boards E adjacent to their upper ends abutting against the end irons H. The clamping-bars F and stay-bolts G are then put in position, the stay-bolts 90 passing behind and pressing tightly against the end boards E. The bolts g are then screwed up tightly upon the ends of the stay-bolts G, thereby tightly clamping the sides and ends of the mold together.

95

The upper edges of the side boards F are provided with side irons I, which may be conveniently made of channel-iron, the upper edges of which irons are provided with properly-spaced notches i. Extending across the 100 top of the mold from side to side are the supporting-irons J, the ends of which j fit with the notches i in the side irons I. These cross-irons are preferably made of angle-iron,

the depending flange of which is cut away at its ends, so that while the ends of the horizontal flange fit within the notches *i* the ends of the depending flange abut against the inner face of the vertical flange of the side irons *I*.

In assembling my mold the nuts *g* upon the stay-bolts *G* should not be fully tightened until the cross-irons *J* have all been placed in position, the nuts being then tightened. The cross-irons are securely clamped between the side irons *I* on each side of the mold and are held rigidly in position thereby. The horizontal flanges of the cross-irons *J* are provided with open slots *j'*. *K* represents supporting-rods, upon which are mounted the inserts *L*. These inserts are properly centered and spaced apart upon the rods *K* in any convenient manner, preferably in the manner described in my concurrent application of even date herewith. As shown, the inserts *L* are provided with perforations. These perforations are of such a size as to furnish a snug fit for the rods *K*. In practice it is found that while such a fit will allow the inserts to be placed upon the rods *K* and to be moved to any desired point the friction between the rods and the under surfaces of said perforations will serve perfectly to hold the inserts suspended upon the rods at any desired point. The inserts having been mounted upon the rods *K*, the rods are placed in the mold between the cross-irons *J*. The upper ends of the rods are then placed in the slots *j'* and the lower screw-threaded ends of the rods *K* are screwed into the perforations *c* in the base-plate *C*. This serves not only to properly locate the rods within the mold, but as the lower ends of the rods are screwed into the base-plate *C* the knobs *k* on the upper ends of the rods are brought tightly into engagement with the upper surface of the cross-irons *J*, and so the rods *K* are securely and accurately held in proper position. When all of the rods carrying their inserts have been placed in position, the mold is ready for the plastic or liquid soap, which is poured into the top of the mold between the cross-irons *J* until the mold is filled. When the soap has cooled and solidified, the rods *K* are unscrewed from the base-plate *C* and are drawn directly upward out of the mold and out of the inserts mounted thereon, leaving the mass of soap with a plurality of inserts located therein at regular distances in all directions. The mold may now be taken apart, leaving the mass of soap, with its inserts, upon the trucks, and the soap may then be cut into bars in any usual or convenient manner, each cake containing one of the inserts *L*, or it may be cut into bars, each bar containing a number of inserts regularly spaced apart within the bar.

In case it is desired to make cakes of soap containing oblong inserts, which, if centrally mounted on the rods *K*, as previously described, would have a tendency to sag, each

insert may be mounted upon two of the rods or wires *K*, as illustrated in Fig. 11, which shows a cake of soap containing an oblong 70 insert *L* (indicated in dotted lines) and mounted upon two rods or wires *K*.

In Figs. 6, 7, and 8 I have shown a modification of my device, the object of such modification being to do away with the objections 75 and difficulties which might arise from the length of the rods which might be required in the use of my device in the form shown in Figs. 1 and 2. In all general respects the mold shown in Figs. 6, 7, and 8 is the same as 80 that previously described; but in this modified form I pass the rods *K* horizontally through the mold, the width of which is usually less than its height, thereby enabling me to use shorter rods. In this modified form I provide 85 supports *d'* for the side boards *D*, which supports are attached to the base-board *B* and project outwardly along the side edges thereof. Instead of mounting a base-plate upon the base-board I substitute a side plate *c'*, 90 mounted upon one of the side boards *D*. I provide the inner faces of the end boards *E* with end plates *M*, which are provided with accurately-spaced notches *m*, which receive the ends of the notched bars *N*, which extend 95 horizontally along one side of the mold from end to end. The rods *K* are inserted in this form of the mold with one end screwed into the side plate *c'* and the other end resting in the slots *n* in the bars *N*. While with this form of my invention it is possible to use plain unthreaded rods or even wires or cords and to dispense also with the knobs *k*, I prefer to have the rods *K* screw-threaded at the ends which engage the side plates *c'* and to have the opposite ends thereof provided with the knobs *k*. These knobs are drawn tightly against the outer faces of the bars *N* when the rods are screwed into the side plate *c'*. To protect these knobs from being entirely embedded in the soap and also to prevent leakage from the mold, I provide the side board *O* with recesses *o*, which receive the knobs *k* when the mold is assembled. The inner face of the side board *O*, adjacent to these recesses, 115 is brought in close contact with the outer faces of the bars *N* when the stay-bolts are tightened.

When the modified form of my device has been filled with soap, the recesses *o* will be kept substantially free from soap, and when the soap has solidified and the mold is taken apart the knobs *k* will be found projecting from one side of the soap mass sufficiently to enable their ready manipulation for the purpose of unscrewing the rods *K* and withdrawing the same from the inserts and from the soap.

While I have shown the preferred forms of my improved mold, I of course do not wish to be confined to the exact features of construction therein shown, as these features may be modified in many respects without departing from the spirit of my invention.

Having thus described my invention, what I claim, and desire to secure by Letters Patent, is—

1. In a soap-mold, the combination with a plate at one side of said mold, of a plurality of insert-supporting rods, openings in said plate for receiving the ends of said rods, and means upon said mold disposed oppositely to said plate for receiving the opposite ends of said rods, substantially as described.
2. In a soap-mold, the combination with a plate disposed at one side of said mold, of a plurality of insert-supporting rods, openings in said plate for receiving the ends of said rods, bars disposed across said mold and opposite to said plate, and openings in said bars for receiving the opposite ends of said rods, substantially as described.
3. In a soap-mold, the combination with a plate disposed at one side of said mold, of a plurality of insert-supporting rods having screw-threaded ends, screw-threaded openings in said plate for receiving the screw-threaded ends of said rods, a bar disposed across said mold and opposite to said plate, openings in said bar for receiving the opposite ends of said rods, and means upon said rods for engaging the outer surface of said bar, substantially as described.
4. In a soap-mold, the combination with a plate disposed at one side of said mold, of a plurality of insert-supporting rods, said rods being screw-threaded at one end thereof, screw-threaded openings in said plate for receiving the screw-threaded ends of said rods, a bar disposed across said mold at the side thereof opposite to said plate, a plurality of open slots in said bar for receiving the opposite ends of said rods, and means upon said rods for engaging the outer surface of said bar, substantially as described.
5. In a soap-mold, the combination with a plate disposed at one side of said mold, of a plurality of insert-supporting rods, openings in said plate for receiving the ends of said rods, means disposed across said mold opposite to said plate for supporting the opposite ends of said rods, and means for closing said mold behind said supporting means, substantially as described.
6. In a soap-mold, the combination with a plurality of insert-supporting rods, of means disposed at opposite sides of said mold for supporting the opposite ends of said rods, and means for closing said mold so as to prevent the leakage of soap around said rod-supporting means, substantially as described.
7. In a soap-mold, the combination with a plate disposed at one side of said mold, of a plurality of insert-supporting rods, said rods being screw-threaded at one end thereof, a corresponding number of screw-threaded openings in said plate for receiving the screw-threaded ends of said rods, means disposed

across said mold opposite to said plate for 65 supporting the opposite ends of said rods, openings in said rod-supporting means for receiving the opposite ends of said rods, means mounted upon said opposite ends of said rods for engaging the outer surface of 70 said rod-supporting means, and means disposed opposite to said plate and back of said rods for closing said mold against the leakage of soap, substantially as described.

8. In a soap-mold, the combination with a 75 plurality of insert-supporting rods, said rods being screw-threaded at one end, of means disposed at one side of said mold for engaging the screw-threaded ends of said rods, slotted rod-supporting means disposed opposite to said rod-engaging means, means upon said rods for engaging the outer surface of 80 said rod-supporting means, and means for closing said mold against the leakage of soap around the ends of said rods, substantially as 85 described.

9. In a soap-mold, the combination with a 90 plurality of insert-supporting rods, said rods being screw-threaded at one end thereof, of means for engaging the screw-threaded ends 95 of said rods, a bar disposed at the opposite side of said mold, slots within said bar for receiving the opposite ends of said rods, means upon said rods for engaging the outer surface of said slotted bar, and means for closing said mold against the leakage of soap around the ends of said rods, substantially as described.

10. In a soap-mold, the combination with a base, of side pieces and end pieces, a 100 plurality of insert-supporting rods, said rods being screw-threaded at the lower ends thereof, means disposed at the inner bottom side of said mold for engaging the screw-threaded 105 ends of said rods, notched bars extending along the upper edges of said mold on two of the opposite sides thereof, a transverse bar extending across said mold between said notched bars, means upon said transverse bar for engaging the notches in said notched 110 bars, means upon said transverse bar for abutting against the opposite faces of said notched bars, openings within said transverse bar for receiving the upper ends of 115 said rods, means upon said rods for engaging the upper surface of said transverse bar, clamping means disposed across the outer surfaces of the sides of said mold upon which said notched bars are mounted, and stay-bolts and nuts extending through said clamping 120 means and across said mold, whereby said mold may be clamped together, substantially as described.
